UNITED STATES PATENT OFFICE.

GILBERT BUDD AND GABRIEL T. DAVED, OF PHILLIPSOPRT, NEW YORK.

IMPROVEMENT IN ATTACHING SHOES TO SLEIGH-RUNNERS.

Specification forming part of Letters Patent No. 125,718, dated April 16, 1872.

Specification describing certain Improvements in Attaching Shoes to Sleigh-Runners, invented by GILBERT BUDD and GABRIEL T. DAVED, of Phillipsport, in the county of Sullivan and State of New York.

This invention consists in constructing the main portion of the shoe with oblique tenons to fit into corresponding mortises in the under sides of the runner.

The main portion of the shoe may be made in two or more parts, connected by oblique V-shaped joints, and secured firmly in position by the front part of the shoe or banger, as it is technically termed; or the main part of the shoe may be made in one piece.

In the accompanying sheet of drawing, Figure 1 is a side view of a sleigh-runner, partly in section, as indicated by the line *x x*, Fig. 2, and having a shoe applied to it according to my invention. Fig. 3 is an inverted plan of the same. Fig. 3 is a detail cross-section of the same.

Similar letters of reference indicate corresponding parts.

A represents a sleigh-runner, and *B B' B''* a shoe composed of three parts. The rear parts *B B'* comprise the shoe proper, the front part *B''* being technically termed the banger. The rear parts *B B'* are each formed with two oblique or inclined tenons, *a a*, at their upper sides, and these tenons fit into corresponding mortises, *b*, in the under side of the runner, and the abutting ends of the parts *B B'* are made to form a V-shaped dovetail, *c*, as shown in Fig. 2, and inclined, as shown in Fig.

1. The abutting ends of *B'* and *B''* are similarly locked together, and *B''* is secured to the runner by bolts and screws *d*, either or both; or the main parts *B B'* of the shoe may be

made in one piece, and provided with two tenons.

It will be seen that the parts *B B'* are secured to the runner without the aid of bolts or screws, and will be firmly secured in position, as they cannot move in any direction; and they may be readily detached, whenever necessary, by unscrewing or unbolting the banger *B''*.

The main parts *B B'* of the shoe, whether made in one or more pieces, is made with a tongue, *b'*, running along the center of its upper side, which enters a groove in the center of the under side of the runner to strengthen the shoe against side movement.

By this construction neither the shoe nor runner will be weakened by bolt-holes. There will be no bolt-heads to wear off, and the wearing surface of the shoe will be perfectly smooth. This construction strengthens both the shoe and runner, and enables the shoe to be easily detached, when required.

Having thus described our invention, we claim as new and desire to secure by Letters Patent—

Attaching the main portion of the shoe to the runner, by providing the former with oblique or inclined tenons *a a*, and tongue *b'*, to fit into corresponding mortises and groove in the runner and having the abutting ends of the parts, when made in two or more pieces, made in the form of an inclined V-shaped dovetail, and the front part or banger bolted to the runner, substantially as shown and described.

GILBERT BUDD.
